Specification of Letters Patent.

Patented Aug. 3, 1920.

Application filed July 15, 1907. Serial No. 383,874.

To all whom it may concern:

Be it known that I, EDWARD E. CLEMENT, a citizen of the United States, residing at Washington, District of Columbia, have invented certain new and useful Improvements in Telephone-Exchange Systems, of which the following is a specification, reference being had therein to the accompanying drawing.

10 My invention relates to telephone exchange systems, and particularly to semi-automatic systems in which automatic switches or their equivalent are employed to effect interconnection of lines as determined 15 by manual apparatus controlled through the agency of operators. My invention has for its object the provision of a number of sets of switching apparatus sufficient for the probable needs of the service, but not necessarily equal to the number of lines, and most desirably less than the number of lines; the provision of operators' controlling sets less in number than the number of lines, and the distribution of the load, that is to say, the 20 25 incoming calls, among the sets of switching apparatus, and among the operators, whereby uniform efficiency in service may be attained.

For the sake of simplicity in description 30 I shall specify herein automatic switches of the type known as "Strowger" selectors and connectors, the construction of such switches being well shown in Letters Patent No. 815,176 and No. 815,321, granted to Keith 35 and Erickson, March 13, 1906. The circuits commonly employed with these switches are well known to those skilled in the art. I shall also specify a type of common battery line circuits and central office talking circuits which are considered standard, and generally known as two-wire bridged battery circuits. It is to be understood however that in specifying the apparatus and circuits mentioned they are used as types 40 45 for purposes of description, and not as limiting the invention.

Stated in terms of the embodiment thus presented, the present invention comprises a number of groups of selector and connector switches less than the number of lines to be served; a number of primary selector switches normally set back to a fixed or zero position, and adapted to connect the calling lines with the said groups of selector and connector switches; a number of operators'

selective keys and impulse transmitting means controlled thereby, with automatic secondary selector switches normally set back at a zero or idle position, and acting to connect the trunks from the primary selector switches to the operator's apparatus when the calls are received, whereby the operators may talk with the calling subscribers, and may actuate the appropriate selector and connector switches to connect the calling and the wanted lines.

By having all the primary and secondary selector switches normally set back to zero, I effect a uniform distribution commencing always with the first trunk or the first position. When a subscriber calls in, current in his line energizes a relay which starts up a primary selector switch, said switch continuing to progress step by step until its wipers connect the terminals of an idle trunk, at which time the cut off relay of the line receives current from the switch circuit, the switch stops, and the secondary selector switch is started to connect the trunk to an idle operator's circuit. An appropriate signaling means such as a lamp, is provided for each operator's circuit, and the operator being thus apprised of a call is able to connect her telephone through her circuit to the trunk and thence to the calling line, and afterward to transmit impulses to the trunk and forward to its automatic first selector switch to secure connection with the line wanted. Testing and ringing of the wanted line are automatic.

The specific distinguishing feature of the invention claimed in the present case is that each trunk has a terminal selector switch by which a subscriber's line may be connected in calling to an idle trunk line leading to a first selector switch; and each trunk line is provided with a switch starting up from a zero or normally inoperative position to select and connect with the controlling and talking circuit of an idle operator. 100 The operator's circuit remains connected to the trunk as long as may be necessary to send the proper impulses for setting the switches which complete the connection, after which the trunk selector switch governing the operator's circuits is returned to zero and remains disabled so long as the trunk is continuously in use. When the subscribers have finished conversing, however, and have cleared out the connection, 105 110

this trunk selector or secondary selector switch again becomes available.

My invention is illustrated in the accompanying drawings in which,—

5 Figure 1 is a diagram showing a calling subscriber's line and a portion of the central office equipment;

10 Fig. 2 is a similar diagram complementary to Fig. 1, and intended to be placed below the latter, showing another portion of the central office circuits;

15 Fig. 3 is a similar diagram also complementary to Fig. 1, intended to be placed at the right of the latter, and showing a selector and connector switch with their circuits through which the calling line may be connected with any one of a considerable number of other lines;

20 Fig. 4 is a diagram of circuits complementary to Fig. 2, intended to be placed at the right of the latter;

Fig. 5 is an end view of an improved rotary selector switch;

25 Fig. 6 is a section on the line X—X of Fig. 5, Fig. 7 shows a modified form of switch similar to that shown in Figs. 5 and 6 some of the parts being omitted. Fig. 8 is a diagram showing the connections whereby the subscriber's lines are connected with 30 the trunk selector operating means in such manner that more than one switch cannot be operated by a single call.

35 Referring to Fig. 1, A is a subscriber's station connected to the central office by line wires 1 and 2 which are normally connected through the contacts of a cut off relay N to the line relay M and the ground, respectively, the line relay being connected to the main battery B through the wire 3. 40 Line extensions 4 and 5 extend from the cut off relay to multiple bank contacts of switches S. Each switch S is a step by step selector switch and is what is called a "single motion" or rotary switch, having a spindle 45 s journaled so that it can turn upon the axis and provided with a ratchet wheel by which it may be turned. This ratchet wheel is engaged by a stop or detent pawl controlled by the electromagnet s', and a stepping or working pawl controlled by the electromagnet s². The mechanical construction of 50 this switch is shown in Figs. 5 and 6 which will be hereinafter particularly referred to. The circuit of the electromagnet s² is controlled by the line relay M through this armature m for which purpose the front contact 7 of the relay is connected by wire 8 with the magnet s², while the armature m is connected through the interrupter I with a 55 battery wire 3. This interrupter is continuously operating and may consist, as shown, of a rotative cylinder having alternating insulating and conducting portions, one conductor being connected with the conducting portion and another with a pen 60 65

bearing upon the cylinder, so that as the cylinder rotates the conductors will be alternately connected together and disconnected as the pen successively bears upon the conducting and insulating portions. The cylinder is continuously driven by any suitable means. With such an arrangement it is only necessary to maintain the circuit closed, when the successive energizations and deenergizations of the magnet and vibrations of its armature will continue indefinitely. In the present case, as the magnet s² vibrates its armature, it also turns the spindle s by means of its pawl and a ratchet on the spindle, and retrograde motion of the spindle being prevented by a stop pawl controlled by the magnet s'. The spindle is provided with a return spring, preferably a coiled spring, which has a constant tendency to turn the spindle back 80 against the pawl of the magnet s', and when this pawl is released by the energization of the magnet will actually turn back the spindle into its normal, zero, or inoperative position. The circuit of the magnet s² in addition to being controlled by the line relay M, is also controlled by the relay R' of the trunk. The release magnet s' is controlled by the relays R and R⁴.

85 In addition to the bank contacts 9 and 10 to which extensions 4 and 5 of the subscriber's line are connected, each switch S is provided with multiple test contacts 11. The wipers 12 and 13 of the switch are adapted to engage, respectively with the 100 bank contacts 9 and 10, while a test wiper 14 is adapted to engage with the bank contacts 11. From the wipers 12 and 13 are trunk extensions 15 and 16, the connection of which with the trunk lines 17 and 18 is controlled 105 by a trunk cut off relay N', which is controlled by the relay R.

110 The relays R and R' are bridged between the two trunk conductors with the main battery B between them. The tip relay R is connected at one side with the conductor 17, the other side being grounded, while the sleeve relay R' is at one side connected to the free side of the battery B and at the other side to the trunk conductor 18. The tip relay R controls the clearings out of the 115 automatic apparatus; the sleeve relay becomes energized when the switch S, of an idle trunk, picks up the calling subscriber and then closes the circuits of the magnets R² and R⁴ which are respectively the stepping magnet of the secondary or operator selector switch S' and a locking relay serving also as a cut off relay for shifting the 120 control as the operator's circuit is connected. The relay R³ is a cut off relay for the operator's circuit wires 19 and 20. The functions of these several relays will best appear from the statement of their operation hereafter.

The relays R^5 and R^6 are combined cut-off and repeating relays. The relay R^5 when energized over the operator's wire 19 pulls up its armature, breaks apart the trunk wires 21 and 23 and connects the latter to the wire 25 leading to the free terminal of the battery B, so as to send an impulse of current through the trunk wire 23. When the relay R^6 is energized over the operator's wire 20 it pulls up its armature to break apart the trunk wires 22 and 24 and connects the latter to the wire 26 which is connected to the free terminal of the battery B, thus sending an impulse of current forward over the trunk wire 24. When both of the relays R^5 and R^6 are simultaneously energized, they connect the operator's wires 20 and 19 to the trunk wires 21 and 22, respectively, so that the operator may connect her telephone to the wires 21 and 22 and communicate with the calling subscriber. It will be observed that the wires 21 and 22 are extensions of the trunk conductors 17 and 18 respectively, to which they are connected by means of condensers C, the condensers being provided to prevent confusion of battery current between the answering and calling ends of the trunk sections. It will also be seen that the conductors 23 and 24 are respectively extensions of the trunk conductors 21 and 22.

The test wiper 14 is connected by a wire 27 with a contact 28 through which circuit is broken when the relay R is energized and, therefore, when the trunk is in use. When the trunk is not in use, and its switch S has been stepped into position to connect it with a calling line connection may be traced from the wiper through conductor 27, contacts 28 and 29, conductor 30 and cut-off relay N' to ground.

It will have been observed that there is one switch S for each trunk, and in order that the switch of an idle trunk may be set in operation to connect a calling subscriber with that trunk, suitable apparatus is provided and further the apparatus is so constructed and arranged that it is impossible for a single call to set in operation more than one trunk switch at a time. The arrangement of the apparatus by which these results are accomplished, is shown in Fig. 8 from which figure portions of the apparatus which are not necessary to an explanation of the features under consideration, have been omitted. Referring particularly to Fig. 8 it will be seen that the conductors 8, 8' and 8² which lead respectively to the stepping magnets s^2 , $1s^2$, $2s^2$, etc., the respective selector switches S, 1S, 2S, etc., are connected together by a conductor 31 so that the energization of any line switch M, 1M, or 2M at any subscriber's station will operate to connect one side of the battery B through the interrupter I with all of the stepping magnets s^2 , $1s^2$, etc. It

will be noted however, that the ground connection of these stepping magnets is made through the back contacts of the armatures r' , $1r'$, $2r'$, etc., of the sleeve relays R' , $1R'$, $2R'$, etc. It will be observed however, that although the ground connection of each of these stepping magnets is made through the back contact of its particular armature r' , $1r'$ or $2r'$ the circuit thus partially made must be completed through the forward contacts of all of those armatures at one side of the armature in question. These forward contacts are only connected when their controlling relays are energized and therefore, only when the trunks to which they correspond are in use. It will now be apparent that it will be impossible for two trunk selector switches to be set in operation by the same call and also that the trunks will be progressively selected by succeeding calls. To illustrate, assuming that none of the trunks are in use, the armature r' is the only one connected with ground as shown in the figure. If now a call is initiated by a subscriber, intermittent battery connections will be made with all of the stepping magnets s^2 , $1s^2$, etc. The magnet s^2 , however, being the only one having a ground connection, this magnet will be the only one energized and will step its switch S into connection with the calling subscriber's line, the other switches $1s$, $2s$ etc., remaining unaffected. The trunk corresponding to the switch S having been thus placed in use, sleeve relay R' will be energized and the ground connection through the armature r' will be placed upon its front contact so that armature is connected with the next armature $1r'$ of a succeeding trunk. Ground is thus placed upon one side of the stepping magnet $1s^2$ so that upon a succeeding call from a subscriber the stepping magnet $1s^2$ will be energized, as was the magnet s^2 , and the switch $1S$ will be stepped into position to connect the second calling subscriber with the trunk corresponding to the switch $1S$. This second trunk having been placed in use, the armature $1r'$ of this trunk will make a ground connection through its front contact for the armature $2r'$ and stepping magnet $2s^2$ of the succeeding trunk and this operation of causing each trunk as it is brought into use to establish connections for the bringing of a succeeding trunk into operation upon the initiation of another call, is carried out to the limit of the apparatus. With the apparatus thus far described it will be seen that if a stepping magnet as $2s^2$ is receiving impulses through armatures as $1r'$ and r' of other trunks, and is stepping its switch $2S$ to connect its trunk with the calling subscriber, and either or both of the trunks through which the circuit of the magnet $2s^2$ is made, is or are cleared out, one or both of the armatures r' and $1r'$ will fall

95

100

105

110

115

120

125

130

back and the circuit of the magnet $2s^2$ will be broken and the operation of the magnet will cease, leaving the switch $2S$ in whatever position it happened to be and confusion of the apparatus might result. To avoid this, contacts a' and b' are provided for each trunk selector switch except the one having its stepping magnet connected with ground through an armature of its own trunk. The mechanical arrangement of these contacts is shown in Figs. 5 and 6 which will be referred to hereafter; these contacts are normally closed but are separated when the switch is in zero position. One of the contacts is connected with the stepping magnet of its switch while the other is connected to ground. The ground connection of the stepping magnet is broken at these contacts, when the switch is in zero position but after the switch has once left that position, the ground connection of the stepping magnet is maintained through these contacts until connection is established with the calling subscriber's line regardless of whether trunks, through which the initial connection for the stepping magnet was made, are cleared out or not.

The trunk wires 23 and 24 extend as shown in Fig. 3 to the side-switch arms s^{10} and s^{12} of the selector switch S^2 . This switch is of the Strowger type referred to in the beginning of my specification, having a main spindle arranged for both vertical and rotary movements, this spindle being placed at the axis of a set of contacts arranged in ten rows of ten each. Carried on the spindle are talking-circuit wipers s^{18} , which coöperate with the bank contacts s^{18} and a test wiper s^{20} which coöperates with the multiple test contacts s^{22} . The switch spindle is stepped up to bring its wipers opposite the desired row of contacts by means of the so-called vertical magnet v controlled through a relay V ; and the rotary movement of the switch is brought about by means of a vibrator magnet v' which makes and breaks its own circuit as it vibrates and is controlled by the relay T when the side switch arm s^8 is in its second or intermediate position. It is unnecessary to give here any extended description of the circuits and apparatus of Fig. 3, all of these being old and well known to those skilled in the art. Q is a release relay of the switch and q is the release magnet governed thereby. The other parts of the apparatus as well as the circuit connections will sufficiently appear from the statement of operation hereinafter.

S^3 designates a connector switch which is designed to coöperate with a selector switch S^2 . It has a similar spindle carrying wipers s^{24} . The test is made on the tip or upper side of the line. The switch also contains line contacts in its banks arranged in rows of ten each. The spindle is stepped up to

bring the wipers s^{24} opposite the desired row by means of a so-called vertical magnet v^3 , and is rotated step by step by means of a so-called rotary magnet v^2 , which in this case is not a vibrator but responds to distinctive current impulses, since the desired line is identified with a single pair of contacts only, and therefore the row of contacts must be selected and the pair of contacts in the row afterward picked out by the wipers, before testing. In this resides the principal difference between the connector and selector switch, the purpose of the selector switch being to pick out and connect with an idle trunk line in any desired group. In the operation of the selector switch, therefore, the spindle is stepped up by means of definite and distinctive impulses to the row of contacts s^{18} and s^{22} representing the desired group (which may be either thousands or hundreds and in this case is hundreds), and after that, when the side switch has taken one step, the rotary magnet v' takes control of the switch and steps the spindle around continuously as long as the wiper s^{20} finds ground on the contacts s^{22} . When this ground fails (the busy contacts being grounded and the idle ones open) it means that an idle contact has been reached, and thereupon the side switch is moved a third step to cut off the rotary magnet and stop the wipers upon this ungrounded or idle contact.

The connector circuit contains a pair of condensers C' for the reason that the forward impulses which work the switch must not be confused by the battery current supplied to the called subscriber. We may assume that the switches of Fig. 3 are both in the same building with the apparatus of Figs. 1 and 2 although this is not at all necessary, and in such case the battery B shown separate in the two figures is of course the same battery. For the purpose of supplying talking current to the called subscriber, I connect this battery to the sleeve conductor 44 of the connector switch, through a relay R^s , and I ground the tip conductor 43 through the relay R^t which is the same as connecting it back to the battery. Thus, the main battery is also bridged across the conductors 43 and 44 through the relays R^t and R^s which as in the case of the relays R and R' in Fig. 1 are wound to approximately 100 ohms each, but present high impedance to voice currents. R^s is a ringing relay, which controls the application of the ringing generator G to the called line and is itself controlled on the one hand by the relay R^{10} and on the other by the commutator K , which may be common to all the ringing relays of the exchange. The circuit of the ringing relay is indicated at 45, 46, 47, 48, 49 and 50, being terminated at the ground through the commutator on one end 130

and at the battery wire 3 on the other end. This circuit is controlled by the relay R^8 , and this relay does not become energized until the side switch arms s^9 , s^{11} , s^{13} and s^{15} have made their last step so that the conductors 43 and 44 are completed from the condensers C' to the wipers s^{24} . Before this last step of the side-switch is taken, the wipers s^{24} have been placed upon the terminals of the wanted line, and the release relay Q' has been applied to the tip side of the line for the purpose of testing. The circuit of this relay is as follows: 51, 52, 53, 54, 55, s^{15} , 56 to the tip wiper s^{24} . If the line wanted is busy, there is a ground on the tip side, either by way of a relay R or by way of a relay R' , depending on whether the line originated the call upon which it is engaged, or was called by some other party. In either case the test or release relay Q' will receive current; but if there is no ground because the line wanted is idle, then the test relay remains unaffected, the talking circuit is completed, and the sleeve wiper relay R^8 becomes energized by current passing to the sleeve s^{24} and thence through the multiple contact 10 of the called subscriber (see Fig. 1) and the cut-off relay N to ground. The cut-off relay thereupon pulls up and the ringing relay circuit is at the same time completed so that the commutator K takes control thereof. It will be observed that this circuit 46-47, etc., passes through a back contact on the relay R^{10} , which is controlled on one side by a pair of contacts under the foot of the spindle of the switch S^3 , and on the other side by front contacts of the tip relay R^7 which does not pull up until the called subscriber answers. When this occurs, the relay R^{10} becomes energized, locks itself by way of wires 50 and 57, and opens the ringing relay circuit 46, 47, 48, etc. The relay R^9 is controlled by the subscriber in the intervals of ringing, for it will be observed that the commutator K has segments whereby it closes the ringing circuit at intervals only. While this circuit is open, therefore, and the relay R^9 deenergized in consequence, the subscriber has control of the relay R^7 . In order that the relay R^8 may remain energized through the ringing intervals, I provide a special battery connection, as shown.

The arrangement of switches shown in Fig. 3 is sufficient for exchanges up to 1000 line capacity; but in order to provide for more than 1000 lines, another set of selector switches is required, interposed between the trunk ends of Fig. 1 and the switch S^2 of Fig. 3. The capacity of the exchange can be increased indefinitely without altering these circuits by adding these sets or groups of switches in the well understood manner. The selector switches all have the same circuit as that shown at S^2 and therefore I

have considered it unnecessary to multiply illustration by showing more than one. It is within the power and skill of every person having a fair knowledge of the automatic art to add as many sets of selectors as may be desired. Regardless of the number of switches, the method of operation, which has an important bearing upon the operator's equipment, is to send the selecting or working impulses over the trunk wire 23, 75 which is commonly called the vertical wire, and to send the controlling impulses over the trunk wire 24 which is commonly called the rotary wire. These so called rotary impulses serve to work the side-switch magnets T and T' , and thereby to shift the side switches so as to bring into play successively the vertical and rotary magnets, the test relay, etc. Referring now to the lower part of Fig. 1 and Fig. 2, I have therein shown an operator's equipment and the trunk selector switch for connecting a calling trunk therewith. The trunk switch is marked S' and is similar in its construction to the primary selector or line switch S . The mechanical structure 90 of this switch will be described hereinafter in connection with Fig. 7. It has a spindle s^{28} , and wipers s^{29} , s^{30} and s^{31} . It is rotated by means of a pawl and ratchet actuated by a vibrator magnet R^2 , and is held in the position to which it is turned by a stop pawl controlled by the release magnet s^{33} . The circuit of the rotary vibrator magnet is closed through an interrupter I' similar to I by the sleeve relay R' of the trunk and 100 opened by the relay R^4 , which it will be recalled is controlled by the relay R^5 , which receives current when an idle operator's set has been reached. The release magnet s^{33} has its circuit controlled by contacts c and d 105 actuated by the switch spindle and the relay R^3 , which is controlled by the contacts d and e , actuated by the switch spindle, and the relays R^4 and R' . In order to enable this description to be followed readily, I may 110 state again that the switch S' starts up from zero as soon as the sleeve relay R' of the trunk has pulled up, that is to say as soon as the trunk 17-18 comes into connection with a calling line. The wipers s^{29} , s^{30} and s^{31} then sweep over the contacts s^{34} , s^{35} and s^{36} of the respective operator's wires, until they reach the contacts of an idle operator's set, when the switch S' is stopped. After the operator has performed her functions 120 and the connection through the trunk wires 23-24 is completed to the wanted subscriber's line, the release magnet s^{33} restores the switch S' to its zero or inoperative position where it remains during the continuance 125 of the connection.

In the lower part of Fig. 2 I have shown the apparatus which appears in front of one operator, consisting of a set of buttons only. Above these in the figure I have 130

shown a set of wheels or sections of a drum with the coöperative springs, the motor and the common commutator of the central office sending machine. This machine furnishes 5 the impulses by which the selector and connector switches are worked in order to select the line wanted, and the number of impulses sent as well as their arrangement is determined by means of the operator's keys or 10 buttons. These keys are in three sets, K, K' and K², each set having ten buttons controlling contact springs k', k². The springs k' of all the buttons in each set are joined to a common wire, and the ends of these three 15 common wires are connected together at the point k*, from which point the conductor 70 leads as shown in Figs. 2 and 1, to the multiple contacts s³⁶ in the banks of the various trunk switches S' of the answering trunks 20 17, 18, 21 and 22. The spring k² of each key is connected to a pen on the appropriate disk or zone on the sending machine drum. When any particular button is depressed, therefore, it connects its individual wire to 25 the common wire 70. The individual wires of the keys K² are marked respectively 71, 72, 73, 74, 75, 76, 77, 78, 79, 80. Similarly the individual wires from the key K' are marked 81, 82, 83, 84, 85, 86, 87, 88, 89, 90, 30 and the individual wires of the keys K are marked 91, 92, 93, 94, 95, 96, 97, 98, 99, 100. The sending machine comprises the main commutator D, having a brush d connected to the main battery, and riding over its 35 segments so as to produce regular recurring makes and breaks in a continuous series. In practice this commutator is made with a pair of spring contacts and teeth or cams are formed on the body of the commutator 40 to work these springs up and down, but for convenience of illustration I have shown the brush resting directly on the periphery of the disk. With such a construction in actual practice and considering that this 45 commutator will carry a large number of switching impulses simultaneously, I prefer to make the brush d of carbon. This is a detail, however, which may be varied at will and does not affect the invention. The 50 commutator D is graphically shown as carried on a shaft d⁰ which extends through all of the number wheels forming both the mechanical and electrical connection therewith. The mechanical connection is not 55 shown in the drawing but the electrical connection is indicated by a wire marked d⁰. The number wheels are shown at d', d², d³, d⁴, d⁵, d⁶, d⁷, d⁸, d⁹, d¹⁰, each having a tooth or raised segment of a suitable length to 60 cover the space of the number of teeth on the commutator D equal to the number of impulses the particular wheel is to transmit. Thus the first wheel d' has a single tooth d¹¹, approximately equal in length to only one 65 tooth on the main commutator. The second

wheel has a single tooth d¹² approximately equal in length to two teeth on the commutator, and so on. In other words, instead of using a set of number wheels each of which makes and breaks through a number of teeth, I have all the makes and breaks on the main commutator, and in order to send any desired number of impulses, I select a wheel which will maintain connection with the commutator while the desired number of impulses are being produced and are then cut off therefrom. Another peculiarity of the arrangement is that the makes and breaks on the number wheels d', d², d³, etc., are made during the passage of gaps 70 on the main commutator when there is zero potential, and hence there will be no sparking at the number wheel contacts. In order to do this I may either subdivide the commutator surface evenly and equally into 75 alternate conducting and insulating segments and then make each number wheel tooth slightly longer than the particular tooth to which it corresponds, or I may make the conducting portions on the commutator smaller than the insulating portions and make the number wheel teeth of lengths equal to the exact multiple of a unit subdivision. 80

It will be observed that there are four sets 95 of pens on the number wheels. These will accommodate four sets of keys K', K², etc. If a greater number of digits appear in the numbers to be transmitted, the wheels must be provided with additional sets of springs. The set K has its individual wires connected to the first set of springs d¹³, the set K' has its individual wires connected to the set of springs d¹⁴, and the keys K² are similarly connected to the spring pens d¹⁵. The general direction of rotation of the commutator and the various wheels connected to it is clockwise as shown by the arrows in Fig. 2, and the teeth on the wheels come in contact with the spring pens in the order d¹³, d¹⁴, 100 d¹⁵. Thus the number set up on the set of buttons K is transmitted over the wire 70 first, then follows the number set up on the button K', and so on. Thus for the number 468 the operator would depress the fourth 105 button in the set K, the sixth button in the set K' and the eighth button in the set K². By tracing the circuits it will be found that when the controlling circuits are closed, which occurs at the beginning of a rotation 110 when the wheels are all in the position shown in Fig. 2, current will pass from the main battery to the commutator D, thence to the wheel d⁴, thence by wire 94 to the fourth key in the set K and thence to the 115 wire 70 and so on to the wire 19 and the relay R⁵ in Fig. 1, which repeats the impulses over trunk wire 23 to the switches. As the wheels continue their rotation, this 120 circuit will be broken after four impulses 130

have been transmitted, and then a new circuit will be formed carrying current from the battery through the commutator to the sixth wheel d^6 , and thence from the second 5 spring d^{14} on that wheel through the wire 86 to the key which is closed, thence to the wire 70 and thence again to the relay R^5 which repeats to the switches. After these impulses have been sent by this route, this 10 circuit will be broken and a new circuit will be formed from the main battery through the commutator D to the eighth wheel to the third pen thereon, d^{15} , thence to the eighth key in the set K^2 , which has been closed, 15 thence to wire 70 and to the relay R^5 as before. The closures between the wheels and successive sets of springs are arranged to be separated by intervals, during which no current at all flows to the wire 70. These 20 intervals are necessary in order to permit the switching circuits to be arranged so as to produce the proper results in response to the successive sets of working impulses. In other words, having shown herein a set of 25 Strowger switches, I must provide not only the vertical or working impulses in groups, but I must also provide the interposed or rotary impulses between said groups. This is accomplished by means of the wheel d^{17} 30 which has four teeth set in quadrature, and all adapted to make contact with the single pen d^{18} , which is connected by the wire 170 to the multiple contacts s^{34} in the banks of the various trunk selector switches S' , and 35 thence through the wire 20 to the relay R^6 , which repeats the rotary impulses over the trunk wire 24 to the switches. The wheel d^{17} is insulated from the shaft d^6 , and is grounded through the wire 101, this being 40 necessary because the relay R^6 is connected on its other side to battery wire 3. In other words, the repeating relay R^6 which is controlled by the number wheel is a grounded relay and so the number wheels take battery 45 impulses from the commutator to work it; but the relay R^6 is on battery, hence the rotary wheel d^{17} uses the ground to work the relays. The reason I make one of these relays grounded and the other to battery is 50 in order to pull them both up simultaneously when the operator has her telephone set bridged across the wires 70 and 170 in Fig. 3.

Hitherto the selector switch referred to 55 as S has been referred to only as regards the electric circuits and contacts with which it is associated and in this connection the diagrammatic illustrations in Fig. 1 have been sufficient. The mechanical features of 60 a switch adapted to perform the functions of the switch S of Fig. 1 are shown in Figs. 5 and 6. This switch comprises a frame a on which is mounted a bank b of contacts consisting of ten rows of contacts of three contacts each. The contacts of the different 65

rows are adapted to be successively engaged by wipers c , d and e which are fixed upon the rotatable shaft f , the three contacts c , d and e being respectively insulated from each other. A spring g interposed between the 70 shaft f and a stationary part as the frame, tends to rotate the shaft f to one limit of movement, when the contact arms carried by the shaft will not rest upon any of the bank contacts as shown in Fig. 5. Fixed upon the 75 shaft f is a ratchet h . The teeth of this ratchet are so constructed that a pawl engaging therewith will prevent movement of the shaft under the influence of the spring g . Adapted to engage with the ratchet h are a 80 holding pawl i and a stepping pawl k . The pawl i is pivoted upon the frame and its nose is normally held in engagement with the ratchet by means of a spring l . The pawl k is pivoted to the armature m^2 of the 85 stepping magnet s^2 , which armature is in turn pivoted to the frame of the magnet or upon any other suitable stationary portion. The armature m^2 is normally held retracted by a spring o while the nose of the pawl k is 90 thrown outwardly by means of a spring p extending between the armature m^2 and the tail of the pawl k . The outward movement of the nose of the pawl k is limited and it is guided in its movement by a stationary pin 95 q^3 . In order that the holding pawl i may be disengaged from the ratchet h so that the contacts upon the shaft f may be returned to their normal position under the influence of the spring g ; a magnet s' , known as the release magnet is provided. The armature s^3 of the release magnet is retracted by means of a spring t , this armature being limited in its outward movement by a nut u in screw-threaded engagement with a screw v^3 100 mounted upon the frame of the magnet and extending through the armature s^3 . Obviously the nut u is capable of adjustment along the screw v^3 to permit greater or less movement of the armature s^3 . Carried by the armature s^3 of the release magnet is a resilient arm w which carries a ratchet tooth x' adapted to engage with the lower end of the stationary latch z' . An arm y mounted upon the armature m^2 of the stepping magnet overlaps one end of the arm w and is adapted to draw down one end of that arm so that the lower end of the latch z' will clear the tooth x' when the armature of the 110 stepping magnet is attracted. The operation of the apparatus is as follows: Assuming the parts to be in position as shown, as impulses are supplied to the stepping magnet its armature will be attracted a number of times equal to the number of impulses 115 and at each attraction the pawl k will be thrown forward into engagement with the ratchet wheel and will move that wheel forward a distance depending upon the adjustment of the various parts, which are so ad- 120 125 130

justed that at the first impulse the wipers upon the shaft f' will be moved into engagement with the first row of bank contacts and will be moved to a succeeding row upon each impulse thereafter. The shaft and wipers which it carries will be prevented from retrograde movement by the holding pawl which is forced into engagement with the ratchet h by its spring. A desired row of the bank contacts having been reached in the manner described and the object for which the connection was established having been accomplished, it becomes necessary to return the wipers to their zero or normal positions in readiness for another operation as just described. This restoration is effected by energizing the release magnet s' , when its armature will be attracted, drawing the tail of the holding pawl i with it, and the nose of that pawl will be disengaged from the ratchet h and the wiping contacts will be returned to their initial position. In the next selective operation of the switch, however, it is necessary that the holding pawl i shall engage with the ratchet h to hold the contacts in any position to which they may be stepped. It, therefore, becomes necessary to release the pawl i prior to the succeeding stepping operation, x' being held by s' . This is accomplished by means of the arm y which, upon the first energization of the stepping magnet and the attraction of its armature, will draw down with it the free end of the resilient arm w thereby freeing the pawl i thereupon its nose will be thrown against the ratchet h by the spring l . Carried upon one of the wipers c , and e upon the shaft f , is a projection z of insulating material adapted, in the case of switches 18 etc., when the removable contacts are in their normal position, to bear against one of, and separate the contacts a' and b' which are so mounted as to be insulated from each other but which are normally in engagement. In the particular arrangement shown, it is necessary that the switch S' , instead of being released upon the energization of its release magnet, shall be released upon de-energization of that magnet succeeding an energization of it. The mechanical structure of a switch, similar to that shown in Figs. 5 and 6 but embodying the modifications necessary to accomplish the result indicated, is illustrated in Fig. 7.

Referring to Fig. 7, the ratchet wheel h' upon the wiper shaft f' is adapted to be engaged by a holding pawl i' pivoted upon the frame and having its nose forced into engagement with the ratchet wheel by a spring l' . The ratchet wheel is also adapted to be engaged by a stepping pawl pivoted upon the pivoted armature of the stepping magnet R^2 , the arrangement of the stepping mechanism being the same as shown in Fig. 5. The release magnet s^{38} has an armature,

a retracting spring therefor and adjusting means precisely like the corresponding portions of the switch shown in Fig. 5. The tooth x^2 on the resilient arm w' , however, when the release magnet is energized, instead of snapping behind the tail of the pawl i' so that upon deenergization of the release magnet the pawl will be removed from engagement with the ratchet wheel. The arm y' upon the armature of the stepping magnet overlaps the end of the arm w' , as in the case of the corresponding arms in Fig. 5, so that the holding pawl is released from the arm w' upon energization of the stepping magnet. Three contacts c' , d' and e' are so mounted upon the frame as to be insulated therefrom and from each other. The contacts c' and d' however, tend to engage at their free ends while an insulating projection z' upon one of the wipers bears against the contact d' , when the switch is in its initial position and holds that contact from engagement with the contact c' and in engagement with the contact e' .

The operation of the system can be best set forth by tracing the connections and noting the operations of the various parts of the apparatus which are involved, from the time a call is initiated at the subscriber's station until the conversation has terminated and the apparatus has been restored to its normal condition.

Let it be assumed that a subscriber at a station, as A, desires to converse. He removes the receiver from the hook when the latter rises and establishes a connection, through his transmitter and receiver, between the lines 1 and 2. A circuit is then established from the free terminal of the battery, B, through the wire, 3, line relay, 105 M, armature, n , line 1, subscriber's set, line 2 and armature n' to ground. The relay M, being thus energized, attracts its armatures m and m' a circuit then being established from the free side of the battery B, through conductor 3, interrupter I, armature m and conductor 8, to conductor 31 whence the circuit passes to one of the stepping magnets as s^2 of the trunk selector switches as before explained. From the stepping magnet the circuit passes through the conductor 8^a and the armature r' of the relay R' to ground. The magnet s^2 is then intermittently energized through the interrupter and this results in the reciprocation of the stepping pawl k (see Fig. 5) and the stepping forward of the wipers of the switch S from one row of bank contacts to the next at each energization until the wiper 14 rests upon the contact 11 to which is connected the conductor 11', leading to the front contact of the armature m' , which is connected to the battery conductor 3. From the wiper 14, circuit is made through conductor 27, make-before-break contacts 28 and 29, con- 130

ductor 30 and relay N' to ground. The relay N' being thus energized attracts its armatures 1n' and 2n' and connects the trunk conductors 17 and 18 with the trunk extensions 15 and 16 which are connected to the wipers 12 and 13 respectively.

When the wiper 14 rests on the contact 11, the wipers 12 and 13, rest on the contacts 9 and 10 respectively. The cut-off relay N is therefore connected in series with the relay R' in a circuit which can be traced from the ground through relay N, extension 5, contact 10, wiper 13, extension 16, armature 1n', trunk wire 18 and relay R' to the free side of the battery. The relay N is of high resistance compared to that of relay R and R' and operates on less current so that while the relay N is operated, the relay R' is not operated by reason of the circuit just traced. The relay N, however, is of such resistance that it will carry sufficient current, after the relay R is connected, to hold its armatures after they have been attracted. The relay N being thus energized, attracts its armatures, thereby breaking the circuit of the line relay M at the armature n whereupon the relay M is de-energized and its armatures fall back, thereby breaking the circuit of the stepping magnet s² whereupon the switch stops. The attraction of its armatures by the relay N, connects the subscriber's lines 1 and 2 with the extensions 4 and 5, contacts 9 and 10, wipers 12 and 13, trunk extensions 15 and 16, armatures 2n' and 1n' and trunk conductors 17 and 18 respectively. It will now be seen that the tip and sleeve relays R and R' are connected by means of the connections just traced, in series through the subscriber's instrument and between battery and ground.

The relays R and R' being energized, their armatures will be attracted, whereupon the circuit of the release magnet s' will be broken at the armature r and the armature 1r will come against its front contact 29 which it separates from contact 28, the battery connection of the former contact being maintained through the conductor 40. The armatures 2r and 3r are removed from their back contacts thereby breaking the battery connections which otherwise would be established with the trunk conductors 21 and 22 upon the attraction of the armature 2r⁴ of the relay R⁴. The armature r' of the relay R' on being attracted, leaves its back contact and thus breaks the circuit through the stepping magnet s² and, coming against its forward contact, makes ground connection, through conductor 41 for the stepping magnet 1s² of the next trunk selector switch, as before explained. The attraction of the armatures 1r' and 2r' against their front contacts results in the establishing of ground connections through

the wires 42' and 43' with the armatures r⁴ and 1r⁴ of the relay R⁴, and also with one terminal of that relay.

Circuit may now be traced from the ground through the armature 1r', conductor 42', armature r⁴, conductor 44', stepping magnet R², interrupter I' and conductor 45', to the battery wire. The magnet R² being intermittently energized will reciprocate its pawl, (see Fig. 7 and description thereof) stepping the switch forward.

A function of the relay R³ is to prevent interference with the connecting operation by reason of the passage of the wipers of the switch S' over the contacts s³⁴, s³⁵ and s³⁶ of busy operator's sets. The relay R' having been energized by the connection of the subscriber's line to the trunk, circuit may be traced from the ground through the armature 2r', conductor 43', armature 1r⁴, conductor 102, relay R³, conductor 101, contacts d' and e' which are normally open, but are closed when the wipers of the switch S' are in their initial position, to battery. In this initial position, therefore, the relay R³ is energized through the circuit traced and attracts the armatures r³ and 1r³ thereby breaking the circuit through the operator's wires 19 and 20 so that any contacts which may be made by the wipers connected with the conductors 19 and 20, will have no effect upon the apparatus of the trunk. When the switch S' moves out of its initial position, the contacts d' and e' separate but the battery connection is maintained so long as the wiper s³¹ is passing over busy contacts s³⁶ as, where those contacts are busy, the armature 2r¹¹ will be attracted and circuit to the battery from each of these contacts will be made by the armature just referred to. When, however, an idle contact is reached, the circuit of the relay R³ is broken and is subsequently maintained opened by the energization of the relay R⁴, when the circuit of the relay R³ is broken at the armature 1r⁴. A further function of the relay R³ is to aid in controlling the release magnet s³³ as hereafter will appear.

The stepping relay R² having its circuit closed, as described, the switch S' will be stepped from one position to the next so that its wipers s²⁹, s³⁰ and s³¹ will pass successively over the rows of bank contacts s³⁴, s³⁵ and s³⁶. Upon the arrival of wiper s³⁰, upon the contact s³⁵, circuit may be traced from the free side of the battery B through armature r¹³, conductor 110, magnet R¹¹, contact 111, contact 112, conductor 113, contact s³⁵, wiper s³⁰, conductor 19, armature r³, conductor 114 and relay R⁵ to ground. The relays R⁵ and R¹¹ are thus connected in series and this results in the attraction of their armatures. The attraction of the armature r¹¹ of the relay R¹¹, however, results in the connection of that

armature with the contact 111 and also in the separation of the contacts 111 and 112. This causes the ground connection of the relay R^1 to be made through the armature 5 r^{11} , that armature being connected to ground as shown, while the circuit of the relay R^5 is broken. The relay R^6 is, therefore, energized but momentarily. This momentary energization, however, causes the temporary 10 contact of the armature r^5 with the contact 115 of conductor 106, when circuit may be traced from the conductor 3 through the armature r^5 , contact 115, conductor 106, relay R^4 , conductor 43' and armature $2r^4$ to ground. The relay R^4 is thus momentarily 15 energized and attracting its armature $2r^4$ brings that armature against the contact 116, thereby transferring the battery connection of the relay R^4 from that made 20 through armature r^5 to that made through armature $2r^4$ and conductor 107 to the conductor 3 and the free side of the battery. The relay R^4 thus locks its own circuit so 25 that it remains energized after the relay R^5 has become deenergized. The relay R^4 , being thus energized, its armature r^4 will be attracted, thus breaking the circuit of the stepping magnet R^2 , whereupon the switch S' will stop. The relay R^4 attracts its armature 30 $1r^4$, thereby breaking the circuit at this point of the relay R^3 , whereupon its armatures fall back and connect the operator's wires 19 and 20 with the trunk circuits. The releasing of the armatures of the relay 35 R^3 also results in the falling of the armature $2r^3$ against its back contact which is connected to ground while the armature is connected to the release magnet s^{33} and therefore one terminal of that magnet is 40 grounded.

After the switch S' has left its initial position, the contacts c' and d' come into engagement, thus connecting one terminal of the release magnet s^{33} with the conductor 45 101. When, therefore, an idle operator's equipment has been selected, a battery connection for the release magnet is made through the wiper s^{31} , contact s^{36} , conductor 121 and armature $2r^{11}$ to battery wire 3. 50 The relay R^3 , being then deenergized, the magnet s^{33} is energized and the release mechanism becomes set, as before described, to release the switch S' upon the deenergization of its release magnet.

55 The relay R^{11} having been energized as described, its armatures $1r^{11}$ and $2r^{11}$ will be attracted and circuit can be traced from the battery wire through the armature $1r^{11}$, conductor 120 and the lamp L to ground. 60 The lamp will thus become lighted, notifying the operator of a call. Another circuit can be traced from the battery wire through the armature $2r^{11}$ and conductor 121 to the contact s^{66} , whence circuit will be traced 65 through the wiper s^{31} , conductor 101, relay

R^3 and conductor 102 to a back contact of the armature $1r^4$, but at this point the circuit is opened, due to the energization of the relay R^4 . Connection may now be traced from the conductor 170 through the contact 70 s^{34} , wiper s^{29} , conductor 20, armature $1r^3$ of the relay R^3 , conductor 124, conductor 125 and relay R^8 to battery wire 3. Connection may also be traced from the wire 70 through contact s^{35} , wiper s^{30} , conductor 19, 75 armature r^3 of relay R^8 , conductor 114 and relay R^5 to ground.

Referring now to Fig. 2, it will be seen that the conductors 170 and 70 are adapted to be connected by means of the pressure of 80 a button O with conductors 127 and 128, which lead to an operator's set of usual construction and hence not shown. It will be seen that upon the depression of the button O , that a circuit will be completed from the 85 battery wire at one side of the relay R^6 through that relay the operator's set, and the relay R^5 to ground. Talking current will thus be supplied to the operator's set and also the relays R^5 and R^6 will become 90 energized, whereupon they will attract their respective armatures $1r^5$ and r^6 and one of the operator's conductors 20 will be connected with the trunk conductor 21 while the other operator's conductor 19 will be connected with the other trunk conductor 22. It will now be apparent that the operator's 95 set and the calling subscriber's instrument will be so connected that conversation may be had.

100 The operator's set and subscriber's instrument having been placed in conversational communication as described, the operator inquires of the subscriber the number of the wanted subscriber's station. Let it be assumed that this number is 468. The operator depresses the fourth key of the set K , the sixth key of the set K' and the eighth key of the set K'' . In this manner the conductors 94, 86 and 78 are connected with the 110 common point kx , these conductors being respectively connected with the pen d^{13} of the section drum d^4 , the pen d^{14} of the drum section d^6 and the pen d^{15} of the drum section d^8 . The commutator D is driven by a 115 motor M^3 and, the motor supposed in the particular apparatus shown to be normally at rest, it becomes necessary to start the motor and commutator. To accomplish this, the operator depresses the button O' and 120 thereby connects the conductor 130, which is connected to one terminal of battery to the conductor 131 and thence through the conductor 132 to the relay R^{12} and to ground. The relay R^{12} being thus energized, 125 its armatures r^{12} and $1r^{12}$ are attracted when circuit will be closed from the battery wire through the last mentioned armature, conductor 133 and relay R^{13} to ground. The relay R^{13} being thus energized, 130

- gized, will attract its armatures r^{13} and $1r^{13}$. The circuit of the relay R^{11} to battery through the armature r^{13} is thus broken, but this connection is made through the armature r^{12} of the relay R^{12} whereby the control of the relay R^{11} is transferred from the relay R^{13} to the relay R^{12} . Circuit may be traced also from the motor conductor 134 through the armature $1r^{13}$ and a suitable generator and motor starter as indicated, which may be of any well known or suitable type, to the other motor conductor 135. The motor will thereupon start up and place the commutator in operation. There is also set in operation a starting disk ds , which is of conducting material with the exception of an insulating segment 136 upon which the pen 137 normally rests. After the motor and with it the commutator, starting disk, rotary disk and drum sections are set in operation by the depression of the key O' , as described, the pen 137 will ride off the insulating segment and maintain the circuit initially closed by the depression of the button O' . This circuit being closed, the motor, commutator and disks will continue to revolve until the pen 137 rests upon the insulating segment 136, when the circuit will be broken and the apparatus will stop. During this rotation, first the pen d^{13} , corresponding to the disk d^4 , will be engaged by the contact segment upon the said disk, which is of such a length as to maintain the contact with the pen during four impulses of current through the commutator. The circuit over which these impulses are sent, may be traced from one terminal of the battery to the brush d , thence through the commutator, the conductor do' to the shaft of the drum, thence through the drum to the segment of the disk d^4 , the pen d^{13} , the conductor 94, the contacts of the fourth button of the row K to the point kx , thence through the conductor 70 to the contact s^{35} of the switch S' , conductor 19 and relay R^5 to ground. At each of the four impulses, the relay R^5 will be energized and attract its armature $2r^5$ against its back contact, connected with the battery B. At each impulse, therefore, the tip side 23 of the trunk will be connected with battery and the impulses will be repeated over this side of the trunk to operate the automatic selector and connector switches as before described; the next operation consists of the sending of a rotary impulse, occasioned by the coming in contact with the pen d^{18} of one of the conducting projections upon the disk d^{17} . This action causes the closure of a circuit from the ground through a conductor 101, disk d^{17} , pen d^{18} , conductor 170, contact s^{34} of the switch S' , conductor 20, and the relay R^6 to the battery wire 3. Each projection on the disk d^{17} is of such length as to transmit but one impulse and this impulse passing through the relay R^6 through the circuit just traced, the relay last mentioned attracts its armature $1r^6$ against its back contact, thereby connecting the sleeve side 24 of the trunk momentarily with the battery wire 3, 70 when a rotary impulse is transmitted over the sleeve side for working the side switches of the automatic selector and connector switches as before indicated; after the sending of the rotary impulse described, the 75 conducting segment of the disk d^8 comes in contact with its pen d^{14} , when six impulses are sent over the conductor 86 to the point kx , whence circuit is the same as before, through the relay R^5 and six vertical impulses are transmitted over the tip side 23 of the trunk. The disk d^{17} then sends another 80 rotary impulse over the sleeve side of the trunk as before and eight vertical impulses are then transmitted over the tip side by 85 reason of the contact upon the disk d^8 coming in contact with its pen d^{15} , connected with the conductor 78 through which connection is established to the point kx , the circuit being otherwise the same as before, through 90 the relay R^5 , and eight vertical impulses will be transmitted over the tip side 23 of the trunk; this is followed by the sending of a rotary impulse by the disk d^{17} and then the apparatus is brought to a stop by reason 95 of the pen 137 riding upon the insulating segment 136.
- At the close of the operation just described, the wanted subscriber's line, unless it is busy, will have been connected 100 as below described. The entry of the pen 137 upon the insulating segment 136 at the end of the connecting operation, breaks the circuit as before traced through the relay R^{12} , which thereupon releases its armature, thereby breaking the circuit of the relay R^{11} which in turn releases its armatures, thereby breaking the circuit of the release magnet s^{33} , when (see Fig. 7) the holding pawl i' will have its nose removed 105 from engagement with the ratchet upon the switch shaft and the switch will return to its zero position, thus leaving the operator's set idle in readiness to perform the connecting operation for another connecting trunk and its subscriber's instrument. The circuit of the relay R^{13} will be broken at the armature $1r^{12}$ whereupon the motor circuit will be broken at armature $1r^{13}$.
- A brief statement of the operation of the 110 switches shown in Fig. 3 is as follows: Assume the subscriber's line to be selected is numbered 453. Four impulses are sent over the vertical trunk wire 23, energizing relay V, which for each impulse closes circuit of the vertical magnet v , and thereby steps the spindle of switch S^2 up to the fourth row of contacts. A single rotary impulse then comes over the trunk wire 24, 115 energizing the rotary relay which is nor- 120
- 125
- 130

- mally connected through the switch arm s^{12} as shown, and which in turn closes circuit of the private relay T, which pulls up, opens the circuit of the vertical magnet v , and mechanically releases by one step the escapement which holds the spring actuated side switch arms s^8 , s^{10} , s^{12} , s^{14} . All these arms pass into the second position, the arm s^8 grounding the rotary magnet v'
- 10 which is connected on the other side to the main battery B, and is adapted to make and break its own circuit so as to form a vibrator. This magnet then steps the switch spindle around so that the wipers s^{16} , s^{20}
- 15 will sweep over the row contacts s^{18} and s^{22} of the ten trunks in the 400 group, testing them for an idle trunk, by successively closing circuit from the contacts s^{22} through the wiper s^{20} and the low resistance release
- 20 relay Q to the test or private relay T. As long as only ground contacts are found, due to their trunks being busy, so long will the relay T be held up as it is in the test circuit with the relay Q. As soon as
- 25 an ungrounded contact is found, the relay T lets go, and kicks the escapement over the second step, so that all side switch arms step off the middle contacts and get on the last ones, the arm s^8 thus cutting off the
- 30 rotary magnet and stopping the rotation, the arms s^{10} and s^{12} completing the talking circuit and disconnecting the vertical and rotary relays therefrom, and finally the arm s^{14} disconnecting the test relay T and grounding the wiper s^{20} through the relay Q for release purposes.
- This operation has connected the trunk wires 23 and 24 to an idle trunk in the 400 group, which we will assume to be the trunk
- 40 43-44. To select line 53 in this group five impulses come over wire 23 to the vertical relay V^2 which grounds the vertical magnet v^3 five times, and steps the spindle of the switch S^3 up to the fifth row of contacts.
- 45 A single impulse then comes over the rotary side 24 and works the rotary relay V^3 , which closes the circuit of the relay T', which in turn kicks over the escapement controlling the side switch arms s^8 ,
- 50 s^{11} , s^{13} , s^{15} , so they will get onto their second contacts. This cuts off the vertical magnet v^3 and cuts on the rotary magnet v^2 . Three more impulses now come over the vertical trunk wire 23 again working the relay V^2 , which however now closes three times in succession the circuit of the rotary magnet v^2 , which steps around the spindle of the switch S^3 so that the wipers S^{24} will rest on the third pair of contacts
- 55 in the fifth row in the banks of that switch. These are the contacts of line No. 453.
- A single rotary impulse now comes over the wire 24 which pulls up the relay V^3 , and closes the test circuit of relay Q' as

follows: from the vertical wiper s^{24} , 56, 65
 s^{16} , 55, 54, 53, 52, Q', 51, B and ground. The test is for a ground, because if the line is busy either a grounded relay as R in Fig. 1, or a similarly grounded relay as R' in Fig. 3, will be connected to the tip side thereof. If the line is thus busy the relay Q' will pull up on the test and close the circuit of the release magnet q' of the connector switch, which will thereupon restore. When the calling subscriber hangs up his receiver, and the relay R lets go, simultaneous impulses over the wires 21-23 and 22-24 will energize both relays V^2 and V^3 which will close the release circuit 39, s^{14} , 38, Q, s^{20} , s^{22} , 64, 52, 51 and battery B. 80 The release relay Q of the switch S^2 will then pull up and close the circuit of its release magnet q whereby the selector switch S^2 will be restored. The circuits of the relays V^2 , V^3 are as follows: for V^2 , 85 from B (Fig. 1), 107, $2r^4$, 116, 106, $2r$, 21, $2r^5$, 23, (Fig. 3) s^{10} , s^{16} , s^{18} , V^2 and ground to battery; for V^3 , from B (Fig. 1), 107, $2r^4$, 116, 106, 3r, 22, $1r^6$, 24 (Fig. 3), s^{12} , s^{16} , s^{18} , V^3 , and ground back to battery. 90

If the line tested is not busy nothing will happen until after the cessation of the test impulse, but the switch arms s^8 , s^{11} , s^{13} , s^{15} will then be kicked over to their third position, completing the talking circuit to the wipers s^{24} , when the relay R^8 will immediately pull up because of the completion of its circuit through the line cut-off relay of the selected line as follows: B, 3, 50, R^8 , s^{18} , s^{24} (see line connections in Fig. 1 which are identical), 10, 5, N, ground and back to battery. As soon as the sleeve relay R^8 pulls up, the ringing relay R^9 will pull up, completing the following circuit: B, 3, 50, 49, 48, 47, R^9 , 45, interrupter K and ground. 105 The ringing relay R^9 will then connect the ringing generator G so as to send its current out over the wanted line at intervals determined by the commutator K. When the subscriber answers, direct current will flow to his line in the intervals of actuation of the relay R^9 and at such time the tip relay R^7 will pull up, closing the circuit of the ringing cut-off relay R^{10} which disconnects the ringing relay and locks itself 115 on a circuit extending direct from the battery through its own armature on one side and through a pair of spring contacts opened by the spindle of the switch S^3 when it is down and closed whenever it is off normal. The relay R^{10} is introduced to prevent ringing back a party after he has hung up. 120

The release of the switches and the general clearing out scheme has already been 125 sufficiently described in connection with the test.

While I have stated that these switching

circuits in Fig. 3 are old and well known, I wish to make one reservation which is that the arrangement of relays R' , R^s , R^s , R^{10} , commutator K , etc., for controlling the 5 ringing, is all original with me, and if not claimed herein will be fully covered in a copending application.

Connections between two subscribers having been established as described, the hanging up of the calling subscriber's receiver 10 breaks the circuit at the hook through his instrument, thereby breaking the circuit of the relay R , whereupon its armatures are released. Its armatures will thereupon be 15 released and fall back and circuit will be traceable from the ground through magnet s' , armature r , conductor 106, armature $2r^4$ and conductor 107 to battery. The release magnet will be energized and (see Figs. 5 20 and 6) the switch S will be released and returned to its initial position. When the wiper 13 leaves the contact 10, the circuit through the relays N and R' will be broken, whereupon their armatures will be released. 25 The releasing of the armature $2r^4$ breaks the circuit of the relay R^4 and its armatures are released. The battery connection to the wire 106 is then broken at the armature $2r^4$. It is to be noted, however, that 30 the relay R^4 is not deenergized until after the relay R has been deenergized and its armatures, including $2r$ and $3r$ have been released. This being the case, it will be seen that the two sides 21 and 22 of the trunk 35 are simultaneously connected with battery. This results in the simultaneous energization of the relays V^2 and V^3 , the circuit of the relay V^2 being traceable from the trunk conductor 43 through the relay V^2 and conductor 65 to ground, while the circuit of the relay V^3 is traceable from the trunk conductor 44 through relay V^3 to ground. Relays V^2 and V^3 having been thus energized and their armatures attracted, 40 circuit may be traced from battery wire 51, release relay Q' , conductor 52, conductor 64, bank contact s^{22} , wiper s^{20} , release relay Q , conductor 38, side switch arm s^{14} and conductor 39 to ground. The release 45 relays Q and Q' being thus energized, will attract their armatures when the circuits of the release magnet q and q' of the switches S^2 and S^3 respectively will be closed, whereupon those switches will be released and 50 will return to their normal positions. The apparatus will then be in its normal inactive condition in readiness for another call. 55

Having thus described my invention what I claim and desire to secure by Letters Patent is:

1. In a telephone exchange system, a number of subscribers' lines, a number of trunks less than the number of lines, each trunk terminating at one end in a primary

selector switch and at the other end in a 65 first selector switch, a plurality of operator's circuits and apparatus, each of said operator's circuits including a telephone set and sending device, and an automatic switch associated with each of said trunks and 70 containing terminals of a number of said operator's circuits, each of the switches specified being normally in a zero or inoperative position, and adapted to be started up to test and connect with bank terminals in 75 their numerical order, substantially as described.

2. In a telephone exchange system, a number of subscribers' lines, a number of trunks less than the number of lines, each trunk 80 terminating at one end in a primary selector switch and at the other end in a first selector switch, a plurality of operator's circuits and apparatus, each including a telephone set and a sending device, and an automatic 85 switch associated with each of said trunks and containing terminals of a number of said operator's circuits, together with release or restoring means for all of said switches, substantially as described. 90

3. In a telephone exchange system, a number of subscribers' lines, a number of trunks less than the number of lines, each trunk terminating at one end in a primary 95 selector switch and at the other end in a first selector switch, a plurality of operator's circuits and apparatus, each including a telephone set and a sending device, and an automatic switch associated with each of said trunks and containing terminals of 100 a number of said operator's circuits, together with driving means for the primary selector switches controlled by the calling subscribers, and driving means for the operator's switches controlled by the primary 105 selector trunks, substantially as described.

4. In a telephone exchange system, a number of subscribers' lines, a number of trunks less than the number of lines, each trunk terminating at one end in a primary 110 selector switch and at the other end in a first selector switch, a plurality of operator's circuits and apparatus, each including a telephone set and a sending device, and an automatic switch associated with each 115 of said trunks and containing terminals of a plurality of said operator's circuits, together with driving means and release or restoring means for the primary selector switches controlled by the calling subscribers, and driving means for the operator's selector switches controlled in the use of the primary selector trunk, substantially as described. 120

5. In a telephone exchange system, a 125 number of subscribers' lines, a number of trunks less than the number of lines, each trunk terminating at one end in a primary

- selector switch and at the other end in a first selector switch a plurality of operator's circuits and apparatus, each including a telephone set and a sending device, an automatic switch associated with each of said trunks and containing terminals of a plurality of said operator's circuits, together with driving means and release or restoring means for said primary selector switches controlled by the calling subscribers, and driving means and release or restoring means for the operator's or secondary switches controlled in the use of the primary selector trunk, substantially as described.
6. In a telephone exchange system, a number of subscribers' lines, a number of trunks less than the number of lines, each trunk terminating at one end in a primary selector switch and at the other end in a first selector switch, a plurality of operator's circuits and apparatus, each including a telephone set and a sending device, an automatic switch associated with each of said trunks and containing terminals of a number of said operator's circuits, together with driving means and release or restoring means for the primary selector switches controlled by the calling subscribers, driving means and release or restoring means for the operator's or secondary switches, controlled in the use of the trunks, and

driving means for the forward or calling selector switches controlled by the operators, substantially as described.

7. In a telephone exchange system, a number of subscribers' lines, a number of trunks less than the number of lines, each trunk terminating at one end in a primary selector switch and at the other end in a first selector switch, a plurality of operator's circuits and apparatus, each including a telephone set and a sending device, an automatic switch associated with each of said trunks and containing terminals of a plurality of said operator's circuits, together with driving means and release or restoring means for the primary selector switches controlled by the calling subscribers, driving means and release or restoring means for the operator's or secondary switches controlled in the use of the trunks, driving means for the forward or calling selector switches controlled by the operator, and release or restoring means for the said calling selector switches controlled over the lines connected, substantially as described.

In testimony whereof I affix my signature in presence of two witnesses:

EDWARD E. CLEMENT.
